(57) **CLAIM**

The ornamental design for a flush timing sensor, as shown.

DESCRIPTION

FIG. 1 is a top, front, right perspective view of the flush timing sensor.

FIG. 2 is a front perspective view of the flush timing sensor.

FIG. 3 is a rear perspective view of the flush timing sensor.

FIG. 4 is a right perspective view of the flush timing sensor.

FIG. 5 is a left perspective view of the flush timing sensor.

FIG. 6 is a top perspective view of the flush timing sensor.

FIG. 7 is a bottom perspective view of the flush timing sensor.

FIG. 8 is a top, front, right exploded perspective view of the flush timing sensor.

FIG. 9 is a front exploded perspective view of the flush timing sensor.

FIG. 10 is a rear exploded perspective view of the flush timing sensor.

FIG. 11 is a right exploded perspective view of the flush timing sensor.

FIG. 12 is a left exploded perspective view of the flush timing sensor.

FIG. 13 is a top exploded perspective view of the flush timing sensor; and,

FIG. 14 is a bottom exploded perspective view of the flush timing sensor.
